UNITED STATES PATENT OFFICE.

THOMAS HOOKER, OF SYRACUSE, NEW YORK.

TWIST-DRILL.

SPECIFICATION forming part of Letters Patent No. 274,943, dated April 3, 1883.

Application filed May 3, 1882. (No model.)

To all whom it may concern:

Be it known that I, THOMAS HOOKER, of Syracuse, in the county of Onondaga, in the State of New York, have invented new and useful Improvements in Twist-Drills, of which the following, taken in connection with the accompanying drawings, is a full, clear, and exact description.

This invention relates to an improved process of solidifying and finishing the cutting-edges of twist-drills; and it consists in forming the drill with a diametric enlargement along the cutting-edges thereof, and subsequently compressing said edges to the requisite diameter of the drill, substantially as hereinafter more fully described, and set forth in the claim.

To enable others to fully comprehend my invention, I have shown in the annexed drawings one of the means by which the object may be obtained.

Figure 1 represents a transverse section of a set of rollers arranged to receive between them the drill to be compacted at its cutting-edges; and Fig. 2 is a transverse section of a twist-drill, illustrating its form before it is subjected to the compression of its cutting-edges.

The drill is brought to the approximate size and form by any of the usual methods, but leaving the forward or cutting edges, *a a*, of the spiral or twisted ribs *b b* projecting somewhat over the requisite diameter of the drill, as illustrated in Fig. 2 of the drawings. The drill in this condition is subjected to circumferential compression by two parallel horizontal revolving rollers, *R R*, which are arranged at a slightly less distance apart than the diameter of the finished drill, the drill to be treated

being carried on a third roller, *r*, or other suitable support, which is situated between the rollers *R R* and below the axis thereof, and presses the drill against said rollers with sufficient force to cause them to compress diametrically the projecting metal *a* at the cutting-edges of the spiral ribs *b* and bring the drill to its requisite true cylindrical external form, as indicated by dotted lines in Fig. 2 of the drawings. The aforesaid compression solidifies the metal at the cutting-edges and materially improves the general finish of the drill.

The process of compressing the cutting-edges can be applied to the drill either in a heated or cold condition, the latter being generally preferred.

I do not limit myself to the use of rollers, as it is evident the same result may be obtained by dies or other mechanical means.

Having described my invention, what I claim as new, and desire to secure by Letters Patent, is—

The within-described process of solidifying and finishing the cutting-edges of twist-drills, the same consisting in forming the drill with a diametric enlargement along the cutting-edges thereof, and subsequently compressing said edges to the requisite diameter of the drill, substantially as specified.

In testimony whereof I have hereunto signed my name and affixed my seal, in the presence of two attesting witnesses, at Syracuse, in the county of Onondaga, in the State of New York, this 28th day of April, 1882.

THOMAS HOOKER. [L. s.]
